UNITED STATES PATENT OFFICE.

WILLIAM SHAKESPEARE, JR., AND WILLIAM SCHMID, OF KALAMAZOO, MICHIGAN,
ASSIGNORS TO WILLIAM SHAKESPEARE, JR., COMPANY, OF KALAMAZOO, MICHIGAN.

CARBURETER.

1,183,125.

Specification of Letters Patent.

Patented May 16, 1916.

Application filed July 22, 1914. Serial No. 852,350.

To all whom it may concern:

Be it known that we, WILLIAM SHAKESPEARE, Jr., and WILLIAM SCHMID, citizens of the United States, residing at Kalamazoo, Michigan, have invented certain new and useful Improvements in Carbureters, of which the following is a specification.

This invention relates to improvements in carbureters.

- 10 The main objects of this invention are: First, to provide an improved carbureter in which the proper relative proportions of fuel and air are maintained throughout varying running conditions of the engine. 15 Second, to provide an improved carbureter in which the air and fuel valves are simultaneously operated or the fuel valve may be independently operated and adjusted. Third, to provide an improved carbureter 20 which is capable of being adjusted for proportioning the air and fuel and one in which the proportion is maintained throughout the scope of adjustment of the throttle. Fourth, to provide in a carbureter, an improved valve mechanism which is not likely 25 to get out of repair or adjustment in use and one which is very simple and easy to operate.

Further objects, and objects relating to 30 structural details, will definitely appear from the detailed description to follow.

We accomplish the objects of our invention by the devices and means described in the following specification. The invention 35 is clearly defined and pointed out in the claims.

A structure which is a preferred embodiment of our invention is clearly illustrated in the accompanying drawing forming a 40 part of this specification, in which:

Figure I is a side elevation of our improved carbureter, certain details of the operating connections therefor being also shown in side elevation. Fig. II is a vertical-central section of our improved carbureter, parts being shown in full lines to better illustrate the same. Fig. III is a view partially in horizontal section, on a line corresponding to line 3—3 of Fig. II. Fig. IV 45 is an end view of the air inlet passage member 3 of the carbureter, looking from the right of Fig. II, with the air inlet valve 6 in position to admit cold air. Fig. V is a perspective view of the air inlet valve 6. 50 Fig. VI is an enlarged detail horizontal

section through the valve operating mechanism on a line corresponding to line 6—6 of Fig. I. Fig. VII is a detail plan view of the valve operating mechanisms with the cap 70 removed. Fig. VIII is a detail perspective view of the valve operating mechanisms with the cap 70 removed. Fig. IX is a perspective view of the member or plate 58 of the auxiliary valve actuating means. Fig. X is a detail vertical section 60 through the valve actuating means on a line corresponding to line 10—10 of Fig. VII. Fig. XI is a front view of the fuel and air regulating levers. Fig. XII is a detail vertical section on a line corresponding to 70 line 12—12 of Fig. XI.

In the drawing similar reference characters refer to similar parts throughout the several views, and the sectional views are taken looking in the direction of the little 75 arrows at the ends of the section lines.

Referring to the drawing, the body of our improved carbureter as shown, for convenience in manufacturing and assembling, consists of members 1, 2 and 3. These members 80 are chambered or provided with a passage. The passage in the member 1 constituting a mixing and delivery passage and the passage of the member 3 constituting a supply or inlet passage and being provided with 85 cold and hot air inlets 4 and 5 respectively. The connection for the hot air inlet to a suitable source of supply is not shown as it will be readily understood.

The air inlet valve 6 is rotatably mounted 90 in the body member 3 and is adapted to cut off either of the inlets 4 and 5 entirely or to permit either being partially opened. Screws 7 are provided as stop members for the valve 6.

The body member 2 is provided with an annular fuel reservoir 8 with an offset inlet chamber 9 at one side thereof. The body member 1 has an internal annular shoulder 10 into which the body member 2 100 fits, see Fig. II, the parts being secured together by the screws 11, see Figs. I and III. The body member 3 fits the annular shoulder 12 at the lower end of the body member 2 and is retained by the screws 13, see Figs. 105 I and II.

The member 2 is provided with a shoulder-like annular valve seat 13 for the throttle valve 14. The throttle valve is provided with a carbureter chamber 15 which deliv- 110

ers through the ports 16 into the chamber above the throttle valve, which constitutes a mixing chamber. The body member 2 is provided with a cross bar 17 having a fuel passage 18 therein communicating with the reservoir 8 and delivering to the nozzle 19 carried by and projecting upwardly from the cross bar into the carbureting chamber 15. The level of the oil in the reservoir 8 and consequently in the nozzle is controlled by the float controlled valve 20. The stem 21 of this valve has a reduced portion or neck 22 with which the forked float lever 23 engages, the lever being pivoted at 24 on the downwardly projecting ears 25 within the inlet chamber. These ears are carried by the cover plate 26 for the inlet chamber. The inlet chamber is provided with a nipple 27 to which the supply pipe is connected. On the valve is a sleeve 28 having a downwardly projecting flange 29. The inlet chamber is provided with a well 30 and with a draw off cock 31 so that any sediment entering is collected and may be drawn off by flushing the reservoir. The nozzle 19 has a reduced portion 32 at its upper end with which the annular carbureting chamber valve 33 coacts. This valve is mounted within the carbureting chamber to coact with the nozzle and its valve proper 34 is made conical. Below this conical part is a sleeve part 35 slidably embracing the nozzle. A series of air inlet openings 36 are provided in said sleeve part. The throttle valve is carried by the main actuating member 37 which is mounted for longitudinal movement in the carbureting body, see Fig. II. The fuel valve 38 projects into the nozzle and controls the delivery therefrom.

The main actuating member 37 is provided with a rack 39 with which the pinion 40 on the shaft 41 coacts. This shaft 41 is provided with an arm 42, see Fig. I, having crank pin 43 thereon engaging the slot 44 in the actuating lever 45, the actuating lever being pivoted on the side of the carburetor body at 46.

A stop screw 47 limits the movement of the lever 45 in one direction. A link 48 connects the lever 45 to a suitable control lever, not shown, commonly mounted upon the steering post 49.

With the arrangement described, the shifting of the actuating lever 45 opens and closes the throttle valve and also the carbureting chamber valve and the fuel valve carried thereby.

The fuel valve is adapted for actuation independently of the carbureting chamber and throttle valves and also means are provided for adjusting the fuel valve so that its normal relation to the carbureting and throttle valve may be regulated to secure the desired richness of mixture. To accomplish

this adjustment a tubular auxiliary actuating member 50 is arranged within the chamber 51 of the main actuating member and sleeved upon the stem of the fuel valve. This member is held evenly against the actuating cam 52 by the spring 53 arranged within the chamber 51 of the main actuating member, one end of the spring being arranged to engage the head 54 of the main actuating member and the other a flange 55 on the auxiliary actuating member. 70 75

The head 54 is provided with a pair of upwardly projecting segmental lugs 56 which serve as supports for the annular cam member 57. Between these lugs is a slotted plate 58 80 having a roller 58' at one end resting on the cam. The other end of the plate has a bearing part 59 riding on the cam member. The plate has a pair of central lugs 60 which engage the under side of the head or nut 61 85 on the auxiliary actuating member so that it is held by the tension of the spring 53 on the cam member. The cam member has an arm 62 connected by the link 63 to the actuating lever 64 which, for convenience, is mounted on the bracket 65 on the steering post 49. This bracket is provided with a notched segment 66 with which the detent 67 on the lever coacts. The segment is provided with suitable indicia indicating the 90 95 position of the fuel valve.

It will be observed that the fuel valve or auxiliary actuating mechanism is carried by the main actuating member so that normally the fuel, carbureting chamber and throttle 100 valves are operated together. The fuel valve may, however, be operated independently to increase or decrease the richness of the mixture for normal running or for starting. We also provide means for adjusting the fuel valve in its normal relation to the throttle and mixing chamber valves. In the structure illustrated this consists of the adjusting screw 68 threaded into the upper end of the auxiliary actuating 105 member to engage the end of the fuel valve stem. A coiled spring 69 acts upon the fuel valve stem to hold against its adjusting screw. A cap 70, carried by the head of the main actuating member incloses the upper end of the auxiliary actuating member and the parts mounted on the head of the main actuating member. 110

The air inlet valve 6 is controlled by the lever 71 mounted on the bracket 65 for the 120 lever 64, the opposite side of the segment 66 being notched to coact with the detent of the lever 71. These levers are both mounted on the same pivot 72, the lever 71 being connected by the link 73 to the arm 74 of the valve 6. The temperature of the air passing through the carburetor may be satisfactorily controlled by this arrangement. 125

The section 1 of the body is provided with 130

a water jacket 75 so that it may be heated if desired.

By this arrangement of parts we provide a structure in which effective control of the fuel is had for starting and effective regulation for normal running and a structure in which proper proportions may be maintained throughout varying running conditions. Certain features of the structure 10 herein described are disclosed and broadly claimed in Letters Patent No. 1,107,713, issued to us August 18, 1914, the present structure being a modification and in some respects an improvement upon the structure 15 there illustrated.

We have illustrated and described our present improvements in the form in which we have embodied the same in practice. We have not attempted to illustrate or describe 20 various modifications which we contemplate as we believe the disclosure made will enable those skilled in the art to embody our improvements as taste or conditions may dictate. We desire, however, to be understood 25 as claiming our improvements specifically in the form illustrated as well as broadly within the scope of the appended claims.

Having thus described our invention, what 30 we claim as new and desire to secure by Letters Patent, is:

1. In a carbureter, the combination of a throttle valve, a chambered longitudinally adjustable main actuating member on which 35 said throttle valve is mounted, said member being provided with a head having upwardly projecting spaced segmental lugs thereon, a fuel valve provided with a head disposed within said main actuating member, an auxiliary actuating member having a flange at its lower end sleeved upon said fuel valve to embrace the head thereof and disposed within said main actuating member, a coiled spring arranged between said 40 head of said main actuating member and said flange of said auxiliary actuating member, an adjusting screw for said fuel valve threaded into said auxiliary actuating member, a coiled spring arranged within said 45 auxiliary actuating member and engaging said fuel valve head acting thereon to hold the same yieldingly against said adjusting screw, an annular cam member rotatably mounted on said main actuating member 50 55 head to embrace said segmental lugs thereof, a plate disposed between said lugs on said head and resting on said cam member at one end and provided with a roller engaging the opposite side thereof, said plate being provided with bearing lugs, a nut on 60 said auxiliary actuating member engaging said lugs, means for rotating said cam member, and means for actuating said main actuating member.

2. In a carbureter, the combination of a

throttle valve, a chambered longitudinally adjustable main actuating member on which said throttle valve is mounted, said member being provided with a head having upwardly projecting spaced segmental lugs 70 thereon, a fuel valve disposed within said main actuating member, an auxiliary actuating member having a flange at its lower end sleeved upon said fuel valve and disposed within said main actuating member, a coiled spring arranged between said head of said main actuating member and said flange of said auxiliary actuating member, an annular cam member rotatably mounted on said main actuating member head to embrace 75 said segmental lugs thereof, a plate disposed between said lugs on said head and resting on said cam member at one end and provided with a roller engaging the opposite side thereof, a nut on said auxiliary 80 actuating member engaging said plate, means for rotating said cam member, and means for actuating said main actuating member.

3. In a carbureter, the combination of a 90 throttle valve, a chambered longitudinally adjustable main actuating member on which said throttle valve is mounted, said member being provided with a head, a fuel valve disposed within said main actuating member, an auxiliary actuating member sleeved upon said fuel valve and disposed within 95 said main actuating member, a spring arranged within said main actuating member to act on said auxiliary actuating member, 100 an adjusting screw for said fuel valve carried by said auxiliary actuating member, a coiled spring arranged within said auxiliary actuating member and acting on said fuel valve to hold the same yieldingly against 105 said adjusting screw, an annular cam member rotatably mounted on said main actuating member head, a plate resting on said cam member and arranged to act upon said auxiliary valve member. 110

4. In a carbureter, the combination of a throttle valve, a chambered longitudinally adjustable main actuating member on which said throttle valve is mounted, said member being provided with a head, a fuel valve disposed within said main actuating member, an auxiliary actuating member sleeved upon 115 said fuel valve and disposed within said main actuating member, a spring arranged within said main actuating member to act on said auxiliary actuating member, an annular cam member rotatably mounted on said main actuating member head, a plate resting on said cam member and arranged to act upon said auxiliary valve member.

5. In a carbureter, the combination with the chambered body, provided with an internal annular shoulder-like valve seat, the chamber above said valve seat constituting a mixing chamber and that below an air sup- 130

4

ply passage, a throttle valve having a carbureting chamber therein delivering to said mixing chamber, a fuel nozzle disposed in said air supply passage projecting into said carbureting chamber, an annular conical carbureting chamber valve arranged within said carbureting chamber and sleeved upon said nozzle to coact therewith, said valve being provided with air inlets opening into said air supply passage, a chambered longitudinally adjustable main actuating member on which said throttle valve is mounted, a fuel valve arranged longitudinally of said main actuating member to coact with said fuel nozzle, an auxiliary actuating member disposed within said main actuating member and sleeved upon said fuel valve, a screw for adjusting said fuel valve within said auxiliary actuating member, a spring within said auxiliary actuating member acting on said fuel valve to hold it against its said adjusting screw, a cam for actuating said auxiliary actuating member mounted on said main actuating member, and a spring arranged within said main actuating member to hold said auxiliary actuating member against said cam.

5. In a carbureter, the combination with the chambered body, provided with an internal annular shoulder-like valve seat, the chamber above said valve seat constituting a mixing chamber and that below an air supply passage, a throttle valve having a carbureting chamber therein delivering to said mixing chamber, a fuel nozzle disposed in said air supply passage projecting into said carbureting chamber, an annular conical carbureting chamber valve arranged within said carbureting chamber and sleeved upon said nozzle to coact therewith, said valve being provided with air inlets opening into said air supply passage, a chambered longitudinally adjustable main actuating member on which said throttle valve is mounted, a fuel valve arranged longitudinally of said main actuating member to coact with said nozzle, an auxiliary actuating member disposed within said main actuating member and sleeved upon said fuel valve, a cam for actuating said auxiliary actuating member mounted on said main actuating member, and a spring arranged within said main actuating member to hold said auxiliary actuating member against said cam.

6. In a carbureter, the combination with the chambered body, provided with an internal annular shoulder-like valve seat, the chamber above said valve seat constituting a mixing chamber and that below an air supply passage, a throttle valve having a carbureting chamber therein delivering to said mixing chamber, a fuel nozzle disposed in said air supply passage projecting into said carbureting chamber, an annular conical carbureting chamber valve arranged within said carbureting chamber and sleeved upon said nozzle to coact therewith, said valve being provided with air inlets opening into said air supply passage, a chambered longitudinally adjustable main actuating member on which said throttle valve is mounted, a fuel valve arranged longitudinally of said main actuating member to coact with said nozzle, an auxiliary actuating member disposed within said main actuating member and sleeved upon said fuel valve, a cam for actuating said auxiliary actuating member mounted on said main actuating member, and a spring arranged within said main actuating member to hold said auxiliary actuating member against said cam.

7. In a carbureter, the combination of an air valve, a chambered longitudinally adjustable main actuating member on which said air valve is mounted, a fuel valve arranged longitudinally of said main actuating member, an auxiliary actuating member disposed within said main actuating member and sleeved upon said fuel valve, a screw for adjusting said fuel valve within said auxiliary actuating member, a spring within said aux-

iliary actuating member acting on said fuel valve to hold it against said adjusting screw, a cam rotatably mounted on said main actuating member for actuating said fuel valve independently of said main actuating member, and a spring within said main actuating member acting on said auxiliary valve actuating member against said cam.

8. In a carbureter, the combination of an air valve, a chambered longitudinally adjustable main actuating member on which said air valve is mounted, a fuel valve arranged longitudinally of said main actuating member, an auxiliary actuating member disposed within said main actuating member and sleeved upon said fuel valve, a cam rotatably mounted on said main actuating member for actuating said fuel valve independently of said main actuating member, and a spring within said main actuating member acting on said auxiliary valve actuating member against said cam.

9. In a carbureter, the combination with the chambered body provided with an internal annular shoulder-like valve seat, the chamber above said valve seat constituting a mixing chamber and that below an air supply passage, a throttle valve having a carbureting chamber therein delivering to said mixing chamber, a fuel nozzle projecting into said carbureting chamber, an annular conical carbureting chamber valve arranged within said carbureting chamber and sleeved upon said nozzle to coact therewith, said valve being provided with air inlets opening into said air supply passage, a fuel valve disposed longitudinally of said throttle valve to coact with said nozzle, an actuating member for said throttle valve, means for adjusting said fuel valve to regulate its normal relation to said throttle and carbureting chamber valves, and means for actuating said fuel valve independently of said throttle and carbureting chamber valves, movable with the said actuating member therefor.

10. In a carbureter, the combination with the chambered body provided with an internal annular shoulder-like valve seat, the chamber above said valve seat constituting a mixing chamber and that below an air supply passage, a throttle valve having a carbureting chamber therein delivering to said mixing chamber, a fuel nozzle projecting into said carbureting chamber, an annular conical carbureting chamber valve arranged within said carbureting chamber and sleeved upon said nozzle to coact therewith, said valve being provided with air inlets opening into said air supply passage, a fuel valve disposed longitudinally of said throttle valve to coact with said nozzle, an actuating member for said throttle valve, and means for actuating said fuel valve independently of said throttle and carbureting

chamber valves, movable with the said actuating member therefor.

11. In a carbureter, the combination with the chambered body provided with an internal annular shoulder-like valve seat, the chamber above said valve seat constituting a mixing chamber and that below an air supply passage, a throttle valve having a carbureting chamber therein delivering to said mixing chamber, a fuel nozzle projecting into said carbureting chamber, an annular conical carbureting chamber valve arranged within said carbureting chamber and sleeved upon said nozzle to coact therewith, said valve being provided with air inlets opening into said air supply passage, a fuel valve disposed longitudinally of said throttle valve to coact with said nozzle, an actuating member for said throttle valve, and means for adjusting said fuel valve to regulate its normal relation to said throttle and carbureting chamber valves.

12. In a carbureter, the combination with the chambered body provided with an internal annular shoulder-like valve seat, the chamber above said valve seat constituting a mixing chamber and that below an air supply passage, a throttle valve having a carbureting chamber therein delivering to said mixing chamber, a fuel nozzle projecting into said carbureting chamber, an annular conical carbureting chamber valve arranged within said carbureting chamber and sleeved upon said nozzle to coact therewith, said valve being provided with air inlets opening into said air supply passage, a fuel valve disposed longitudinally of said throttle valve to coact with said nozzle, and an actuating member for said throttle valve.

13. In a carbureter, the combination of the body provided with a mixing chamber, a throttle valve having a carbureting chamber therein delivering to said mixing chamber, a fuel nozzle projecting into said carbureting chamber, an annular conical carbureting chamber valve arranged within said carbureting chamber and sleeved upon said nozzle to coact therewith, a fuel valve disposed longitudinally of said throttle and carbureting chamber valves, an actuating member for said throttle valve, and means for actuating said fuel valve independently of said throttle and carbureting chamber valves, movable with the said actuating member therefor.

14. In a carbureter, the combination of an air valve, a longitudinally moving main actuated member on which said air valve is mounted, a fuel valve mounted for longitudinal reciprocating movement independently of said main actuating member, an auxiliary actuating member for said fuel valve carried by said main actuating member and movable therewith whereby the air and fuel valves are normally actuated together, means

for adjusting said fuel valve on said auxiliary actuating member whereby its normal operating relation to the air valve may be regulated, and means mounted on said actuated member for reciprocating said fuel valve independently of said main actuating member for opening and closing the fuel valve without operating the air valve.

15. In a carbureter, the combination with an air valve, a longitudinally moving main actuated member on which said air valve is mounted, a fuel valve mounted for longitudinal reciprocating movement independently of said main actuating member, an auxiliary actuating member for said fuel valve carried by said main actuating member and movable therewith whereby the air and fuel valves are normally actuated together, and means mounted on said actuated member for reciprocating said fuel valve independently of said main actuating member for opening and closing the fuel valve without operating the air valve.

16. In a carbureter, the combination of a carbureting chamber, a fuel valve, an air inlet valve for said carbureting chamber, a mixing chamber into which said carbureting chamber delivers, a throttle valve for said mixing chamber, operating connections for said fuel, carbureting chamber and throttle valves whereby they are normally operated together, means for adjusting said fuel valve relative to and for normal operation with said carbureting chamber and throttle valves, and means for operating said fuel valve independently of its said adjusting means and independently of said carbureting chamber and throttle valves.

17. In a carbureter, the combination of a carbureting chamber, a fuel valve, an air inlet valve for said carbureting chamber, a mixing chamber into which said carbureting chamber delivers, a throttle valve for said mixing chamber, operating connections for said fuel, carbureting chamber and throttle valves whereby they are normally operated together, and means for operating said fuel valve independently of its said adjusting means and independently of said carbureting chamber and throttle valves.

18. In a carbureter, the combination of a carbureting chamber, a fuel valve, an air inlet valve for said carbureting chamber, a mixing chamber into which said carbureting chamber delivers, a throttle valve for said mixing chamber, a main operating means having operating connections with said fuel, carbureting chamber and throttle valves, whereby they are normally operated together, an auxiliary operating means for operating said fuel valve independently of said carbureting chamber and throttle valves, said auxiliary operating means being carried by and movable with said main operating means, and means for adjusting said

fuel valve whereby its normal relation to said carbureting chamber and throttle valves is regulated, said adjusting means being carried by and movable with said auxiliary 5 operating means.

19. In a carbureter, the combination of a carbureting chamber, a fuel valve, an air inlet valve for said carbureting chamber, a mixing chamber into which said carbureting 10 chamber delivers, a throttle valve for said mixing chamber, a main actuating means for said fuel, carbureting chamber and throttle valves, whereby they are simultaneously operated together, an auxiliary actuating

means for said fuel valve whereby said valve 15 may be actuated independently of said main actuating means, and means for independently adjusting said fuel valve whereby its normal relation to said carbureting chamber and throttle valves is regulated. 20

In witness whereof, we have hereunto set our hands and seals in the presence of two witnesses.
